UNITED STATES PATENT OFFICE.

GEORGE R. HANKS, OF HIGH BRIDGE, NEW JERSEY, AND GERRITT V. WOOD, OF OAKLAND, CALIFORNIA, ASSIGNEES TO TAYLOR-WHARTON IRON AND STEEL COMPANY, OF HIGH BRIDGE, NEW JERSEY, A CORPORATION OF NEW JERSEY.

DREDGE BUCKET AND LIP THEREFOR.

Application filed June 25, 1924. Serial No. 722,304.

To all whom it may concern:

Be it known that we, GEORGE R. HANKS and GERRITT V. WOOD, citizens of the United States, residing, respectively, at High Bridge, in the county of Hunterdon and State of New Jersey, and at Oakland, in the county of Alameda and State of California, have invented certain new and useful Improvements in Dredge Buckets and Lips 10 Therefor, of which the following is a specification.

Our invention relates more particularly to dredge buckets equipped with so-called "inside-outside" lips, such as disclosed in Letters Patent 1,310,570, granted July 22, 1919, to L. D. Hopfield. While lips of this type possess certain advantages over the ordinary horse-shoe lip, they suffer the disadvantage of too much overhang which is unsupported other than by rivets so that under repeated shifting of the digging strain from one side of the lip to the other, the lip works loose, shears the rivets and tears the bucket.

Objects of our invention are to improve 25 the construction of dredge buckets and lips so that there will be no relative unsupported overhang, no shearing strain on the rivets, and no tendency of the lips to work loose with consequent damage to the hood of the 30 bucket.

With such and other objects in view, the nature, characteristic features and scope of the invention will more readily be understood from the following description taken 35 in connection with the accompanying drawings, forming a part hereof, wherein

Figure 1 is an elevational view of a bucket and lip assembly embodying our invention, a portion of the lip being broken away,

40 Figure 2 is a side elevational view,

Figure 3 is a section on line 3—3 of Figure 2,

Figure 4 is a section on line 4—4 of Figure 1,

45 Figure 5 is a plan view with the lip broken away,

Figure 6 is a section on line 6—6 of Figure 2,

Figure 7 is a perspective view of the lip, 50 and

Figure 8 is a sectional view of a modified form of key or end lock.

According to our invention, the hood 5

of the dredge bucket is provided with a continuous or intact lip seating edge 6; and the 55 side walls 7 of the hood are of gradually increasing thickness rearwardly, the increased wall thickness being symmetrically distributed so as to avoid isolated heavy sections of metal. The purpose of the additional metal 60 in the sides of the hood, aside from strengthening the hood, is to provide for slots or recesses 8 in the inside faces of the walls 7. The recesses 8 co-operate with lip elements 65 to relieve the rivets of shearing and other strains.

The lip 9 has a depending outside flange 10 and a pair of depending inside flanges 11, whose confronting curved edges 12 overlap the flange 10. The flanged portion of the lip has a continuous seat 13, which is adapted to take a flush bearing on the edge 6 of the hood. To provide for the described construction and arrangement of the flanges 70 and the intermediate seat, the lip has its maximum development centrally thereof 75 and tapers towards its digging edge, the taper following the general taper of the hood.

The inside flanges 11 are provided at or 80 in the vicinity of the rear extremities with lateral lugs or offsets 14 of substantially wedge form in the sense that they follow the taper of the lip and therefore are thickest at 85 the bottoms, as at 15. The lugs 14 are designed to enter and fill the recesses 8 of the hood, which conform to the lugs and are of maximum capacity at the bottoms as indicated at 16. Manifestly, regardless of the direction 90 of the digging strain, an adequate bearing is always provided for the lip which accordingly cannot work loose and shear the rivets or damage the bucket. The general taper of the lip from its cutting edge rearwardly is substantially that of the interior of the bucket and hence there are no obstructions to interfere with the filling of the bucket.

The hood has the usual abutment 17 for the outside flange; and the usual rivets are indicated at 18.

In Figure 8, there is illustrated a slight modification wherein the recesses 8 have their end walls undercut, as at 19, to conform to the undercut lugs 20 of the lip. The office of this construction and arrangement is the same as that previously de- 105

scribed, namely, to augment the wedging action of the lip under changing direction of stress.

Having described our invention, we 5 claim:

1. A dredge bucket having its hood formed with a lip seat, a lip adapted to said seat and having flanges inside and outside the hood, the inside flanges having a wedge 10 connection with the hood.

2. A dredge bucket having its hood formed with a marginal seat finished in one plane, and a lip having elements straddling the seat, some of which are keyed to 15 the hood.

3. A dredge bucket having its hood formed with a seat for a digging lip, and with lug seats, and a digging lip applied to said seat and having lugs adapted to the 20 lug seats.

4. A dredge bucket having its hood formed with a marginal seat for a digging lip and with lug seats, and a digging lip applied to said seat and having inside and 25 outside extensions, the inside extensions having lugs for engagement with the lug seats.

5. A dredge bucket having its hood formed with a marginal seat for a digging 30 lip and with lug seats, and a digging lip applied to said seat and having inside and outside flanges, the inside flanges having end lugs adapted to the lug seats.

6. A dredge bucket having its hood formed with a marginal seat for a digging 35 lip, and a digging lip applied to said seat and having an outside flange and inside flanges, the inside flanges having means for establishing a wedge connection with the hood.

7. A dredge bucket having its hood formed with a marginal seat for a digging 40 lip, and a digging lip applied to said seat and having an outside flange and inside flanges, the inside flanges having tapered 45 offsets and the hood having corresponding sockets to establish a wedge action interlock.

8. A dredge bucket having its hood formed with a marginal seat having sockets near the respective ends thereof, and a digging lip applied to said seat and having inside and outside hood engaging extensions, the inside extensions having integral wedge 50 formations afforded bearing in said sockets.

9. A dredge bucket lip having a hood seating portion separated by inside and outside flanges, the inside flanges having integral wedge formations.

10. A dredge bucket lip having a hood seating portion defined by inside and outside flanges, the inside flanges having tapered end lugs.

In testimony whereof we affix our signatures.

GEORGE R. HANKS.
GERRITT V. WOOD.
